UNITED STATES PATENT OFFICE.

JAMES DOYLE, OF NEW YORK, N. Y., ASSIGNOR TO HIMSELF AND PATRICK McNAMARA, OF SAME PLACE.

PIPE-WRENCH.

SPECIFICATION forming part of Letters Patent No. 298,294, dated May 6, 1884.

Application filed October 8, 1883. (No model.)

To all whom it may concern:

Be it known that I, JAMES DOYLE, of New York city, in the county and State of New York, have invented certain new and useful Improvements in Pipe-Wrenches, of which the following is a specification.

My improved wrench is of the kind employing a lever with a roughened surface to bear against the pipe, and chains of sufficient length 10 extending from the lever around the pipe and attached to the lever permanently at one end and adjustable at the other. I have devised means whereby the chains are rapidly and conveniently adjusted with more than usual nicety 15 to adapt the wrench to different sizes of pipe.

The following is a description of what I consider the best means of carrying out the invention.

The accompanying drawings form a part of 20 this specification.

Figure 1 represents the device adjusted for a small pipe. Fig. 2 shows the same adjusted for a large one. Fig. 2^a shows a portion as seen from the opposite side. Figs. 3 and 4 represent modifications. Each is a side elevation of the wrench and a cross-section of the pipe on which it is applied. Fig. 5 is a plan view 25 of the form shown in Fig. 1.

Similar letters of reference indicate corresponding parts in all the figures where they occur.

A is the lever, certain portions being designated by additional marks, as A', when necessary. The surface of the portion which grips 35 on the pipe is curved and finely toothed, as indicated by A'.

B and C are chains of exactly equal length. One end of each is attached to a stout pin, A², which is set transversely at the point 40 represented in the lever A. The other end of each of the chains B C is attached to one end of a locking-piece, D, which is of a little less thickness than the lever A, and is provided with teeth d, uniformly placed on 45 each edge. Three or more holes, a' a² a³, are bored in the lever A, which serve to receive bolts H, which are inserted through the holes in a triangular plate, E. The holes in the lever A are equidistant. By removing and inserting the bolts H anew the position of the

plate E may be changed, so as to be held against any two adjacent holes, a' a² or a² a³. Two or more notches, a* a**², are produced on the upper edge of the lever A, each opposite a point midway between two of the holes. The 55 inner face of the plate E is formed with two stout dogs, M. The lowermost matches in the notch a* when the plate E is held against the holes a' a², and matches in the notch a** when the plate is held against the holes a² a³. The 60 uppermost dog is at such distance from the lower dog and both are of such size and form that when the locking-piece D is properly applied the dogs match each in the notches d of the locking-piece D, the lowermost matching 65 in a notch on the lower edge of D and the uppermost matching in a notch, d, directly opposite, on the upper edge.

In applying the wrench for use, the lever A is held with the notched surface A' against the 70 pipe O, (see Fig. 1,) and the locking-piece D, carrying the attached chains B C, is passed around the pipe, and, drawing the chains as tight as conveniently may be, is presented to the dogs M, so that the latter are received, respectively, in a notch, d, one on the upper and the other on the lower edge of D. The wrench is now ready to operate by being reciprocated. 75 Its motion in one direction will be of no effect. In the other direction, that indicated by 80 the arrow in Fig. 1, the chains will draw the surface into tight contact with the pipe, and the teeth A' will grip the pipe forcibly and compel the pipe to turn with the lever.

My pipe-wrench will serve with a wide range 85 of diameters of pipe, and can be adjusted to fine gradations. Small differences in diameters are allowed for by shifting the locking-piece D forward and backward, so as to engage a different pair of its notches d with the 90 dogs M. Large differences in diameter are allowed for by taking out the bolts H, shifting the piece in one direction or the other, and inserting the bolts H in different holes in A, as a' a², instead of a² a³.

Modifications may be made in the forms and proportions. Parts of the invention can be used without the whole. Fig. 3 shows a construction in which the plate is dispensed with, and in its stead I employ a single hinged dog, 95 100

engaging only with the upper set of the teeth d . The dog is of U form, pivoting or turning on a single bolt, H, which is set in one of the holes a a^2 a^3 . It may be shifted from one hole 5 to another with the same effect in adapting the wrench to large differences of size of pipe as the corresponding changing of the two bolts H in Figs. 1 and 2. To make the minor changes with this modification the dog is lifted and the 10 locking-piece D shifted inward or outward one notch or more, and the dog engaged with a different notch, d . Fig. 4 shows another modification. In this a rigid strap or bracket, K, is applied to embrace the lever A, as shown, 15 and secured by a single bolt, so as to hold it rigidly. Another bolt is inserted in the position represented above the lever A, and when the locking-piece D is presented thereto engages one of the lowermost teeth d . A pin at- 20 tached by a short length of chain, Q, is inserted at will at a higher point in K to engage with one of the notches d on the upper edge of D. This removable pin (marked M') serves 25 as the upper dog to engage in the upper series of teeth, d . The adjustment for different sizes with this modification will be readily understood. The removable pin at the top is drawn

out and the locking-piece D d shifted forward or backward and the pin reinserted, engaging itself and the dog M in different notches, d . 30 For great changes of diameter of the pipe the bolt securing the strap K to the lever A is removed and the bracket K shifted to a new position, and the bolt inserted through a different hole, a' , instead of a^3 . 35

I claim as my invention—

A pipe-wrench having chains B C, a lever, A, with its roughened surface A' and notched locking-piece D d , in combination with each other and with dogging means M, adapted 40 to engage in any of the several notches d , and with means, as H a a^2 , for changing the point of attachment of the dogging means to the lever A, all substantially as herein specified. 45

In testimony whereof I have hereunto set my hand, at New York city, New York, this 28th day of September, 1883, in the presence of subscribing witnesses.

JAMES DOYLE.
